UNITED STATES PATENT OFFICE.

HENRY ROBERT SAMSTAG, OF NEW YORK, N. Y., ASSIGNOR TO SAMSTAG & HILDER BROS., INC., OF NEW YORK, N. Y., A CORPORATION OF NEW YORK.

DESIGN FOR A LEATHER HAND BAG.

Application filed January 26, 1926. Serial No. 16,269. Term of patent 3½ years.

To all whom it may concern:

Be it known that I, HENRY ROBERT SAMSTAG, a citizen of the United States, residing at New York city, in the county of New York and State of New York, have invented a new, original, and ornamental Design for a Leather Hand Bag, of which the following is a specification, reference being had to the accompanying drawing forming part thereof, in which—

Fig. 1 is a plan view of a leather handbag showing my new design.

Fig. 2 shows a side view of the article shown in Fig. 1.

I claim:

The ornamental design for a leather handbag as shown.

HENRY ROBERT SAMSTAG.
